(57) CLAIM

The ornamental design for a dappen dish assembly, as shown and described.

DESCRIPTION

FIG. 1 is a front perspective view of a dappen dish assembly, showing a first configuration of my new design;

FIG. 2 is a top view thereof;

FIG. 3 is a bottom view thereof;

FIG. 4 is a front view thereof;

FIG. 5 is a back view thereof;

FIG. 6 is a left side view thereof;

FIG. 7 is a right side view thereof;

FIG. 8 is a front perspective view of the dappen dish assembly, showing a second configuration of my new design;

FIG. 9 is a cross-sectional view taken along line 9-9 of FIG. 3; and,

FIG. 10 is a front view of the dappen dish assembly showing the second configuration of my new design.

1 Claim, 10 Drawing Sheets(56)
